UNITED STATES PATENT OFFICE.

RODOLPHE RAU, OF GENEVA, SWITZERLAND.

ECONOMIZER ARRANGEMENT FOR LOCOMOTIVES.

1,308,808.

Specification of Letters Patent.

Patented July 8, 1919.

Application filed January 6, 1919. Serial No. 269,822.

To all whom it may concern:

Be it known that I, RODOLPHE RAU, citizen of Switzerland, residing at Geneva, 53 Chemin Moillebeau, in Switzerland, have 5 invented certain new and useful Improvements in or Relating to Economizer Arrangements for Locomotives; and I do hereby declare the following to be a full, clear, and exact description of the invention, such 10 as will enable others skilled in the art to which it appertains to make and use the same.

The economizer for locomotives forming 15 the subject of the present invention has for its object to considerably diminish the fuel consumption in locomotives. It comprises five essential parts, viz: A an evaporative surface condenser, B a vacuum pump, C a pump for the circulation of condensation 20 water, D a servo-motor with or without a dynamo and E a ventilator having a conical tube serving to effect an induced draft.

The invention is described hereinafter in detail with reference to the accompanying 25 drawings which show diagrammatically by way of example two constructional forms of economizer for locomotives.

Figure 1 is an elevation of an evaporative surface condenser installed on a wagon. 30 The suction pump and the circulating pump are disposed in the chassis of the wagon below the platform.

Fig. 2 is a cross section.

Fig. 3 is a plan of the evaporative surface 35 condenser and its tank collector.

Fig. 4 is a plan of the suction pump, the pump for the circulation of condensation water and the servo-motor with its dynamo.

Fig. 5 shows in elevation the draft inducer, the latter being disposed concentrically 40 with the escape pipe.

Fig. 6 is a cross section and Fig. 7 a half plan of the draft inducer and the ventilator.

Fig. 8 is an elevation of a modified form 45 of draft inducer which is disposed, for example in front of or behind the escape pipe and independently thereof.

Figs. 9 and 10 show in plan and elevation the arrangement of an economizer on a locomotive tender.

Referring to the drawings A indicates the evaporative surface condenser formed by the serpentine tubes of iron, F is an escape

steam distributer, G a collector for the condensed products, H the pipe communicating 55 between the condenser and the vacuum pump. I is the escape pipe from the suction pump leading the condensed products into the collector tank N. C is the circulating pump, J the suction pipe taking water from the bottom of the tank N. K is a pipe delivering water into the distributing tank L. M are tubes serving for the distribution of condensation water to the serpentine tubes 60 of the condenser. N is a tank collector for the condensation water. O designates the shutters which prevent the water from passing outside the tank N. D is a servo-motor comprising a steam turbine and a dynamo S. 65

E indicates the ventilator for the induced draft. P the conical tube of the air ejector concentrically disposed to the escape steam tube or pipe. Q is a three way valve. R is the escape steam pipe which leads to the collector F. In the modification T indicates 70 the conical pipe for the induced draft arranged independently of the escape steam pipe and U the second funnel for this induced draft.

In Figs. 5 and 6 the steam flows through 80 the three way valve. One of the positions of this valve corresponds to the free escape of exhaust steam and the other to the path of the condensation. During the flow of the condensation water, the steam is delivered 85 by the pipe R to the distributer F of the evaporative surface condenser. This escape tube passes, in locomotives of small dimensions above the boiler and in large locomotives it extends along the chassis as indicated in Fig. 6. 90

In its passage between the locomotive and the tender on the one hand, and the tender and the condenser way on the other hand, a metallic blower or a flexible tube is interposed in the escape pipe in such manner as to compensate for variations in length and in level.

The exhaust steam is delivered from the distributer F Figs. 1 and 3 into the serpentine tubes of the evaporative surface condenser A. These tubes are mounted above the tank collector and rigidly connected by a metallic framework. The condensation water taken into the tank collector N by the 105 circulating pump is returned to the reser-

voir or tank L, from which are supported a number of distributing tubes M split at their lower parts throughout their length which tubes direct the condensation water 5 in cascade on the serpentine tubes A.

The cooling of the condensation water is effected by its partial evaporation in contact with air and on account of a great speed of the latter which speed is induced by 10 the speed of the train, the cooling action becomes very intense.

The condensed vapor is drawn in by the pump B and delivered through the tube I into the tank collector N. It serves therefore to hold the surplus or excess water.

Theoretically the weight of the condensed vapor being equal to the weight of the water evaporated, the only loss of water will be that which results from the entrainment 20 of a small quantity of this water by the air.

The suction pump B, the circulating pump C, the servo-motor D and its dynamo see Figs. 1, 2 and 4 are mounted on a base plate which is suspended below the wagon 25 platform and integral with the chassis of the wagon.

In large locomotives the servo-motor will be a turbo alternator on the axis of which will be keyed a toothed wheel which by 30 means of a chain drive actuates the shaft of the centrifugal pump C; on the free end of the shaft of this pump is keyed a crank which controls the beam or lever of the pump B, this latter being constructed to 35 operate at a high speed.

The dynamo S which is assembled with the servo-motor D provides the electric energy for operating the electric ventilator E, see Figs. 6 and 7. This ventilator is 40 installed on one of the platforms of the locomotive. The air delivery pipe or tube does not pass through the smoke box as indicated diagrammatically and for clearness in Fig. 6; but in order not to impede the cleaning of 45 the tubes, it will pass as indicated in Fig. 5 in front of the exhaust pipe and axially therewith.

The conical pipe P see Figs. 5 and 6 is concentrically disposed with respect to the exhaust pipe. It is demountable as well as the air supply pipe.

In the modification shown in Fig. 8, the conical tube T for the induced draft is quite independent of the exhaust pipe to the atmosphere. It will be placed, in front, or behind the latter, but always axially of the exhaust pipe, in order to facilitate the cleaning of the boiler tubes. The smoke box will in this case be provided with a second funnel. The two funnels will have a common swinging or balanced cover, which will close one or the other funnel.

In locomotives of moderate power, the servo-motor will be a small double acting

steam engine, which will actuate the suction pump B, the circulating pump C and the ventilator E. These members may be grouped on two gangways or bridges on the locomotive and the evaporative surface condenser will not be mounted on a special wagon, but will be installed on the tender, it may be on the water tank, or to right or left thereof.

In tender or tank locomotives see Figs. 9 and 10 the evaporative surface condenser A is disposed on each side of the boiler and the servo-motor D the suction pump B, the circulating pump C and the ventilator are grouped on two gangways or bridges to the left and right of the boiler, the circulating 75 pump and the ventilator being mounted on a common shaft which will be controlled by the fly wheel of the servo-motor.

Considering that the exhaust always takes place into the atmosphere at a considerably 80 high counter pressure, which counter pressure is necessary to cause the draft, working with condensation will present a very large economy despite the energy which will be consumed on the one hand by the servo-motor, the vacuum pump, the circulating pump and by the induced draft ventilator and the energy which on the other hand will be taken from the locomotive in order to draw the condenser wagon.

I claim:

1. An economizer system for locomotives, comprising a condenser, a collector, means for forcing the water of condensation to the collector, means for distributing the water 100 of condensation over the condenser, a ventilator for creating a draft through the locomotive stack, and means for selectively causing the flow of the exhaust steam through the stack or to the condenser.

2. An economizer system for locomotives, comprising a condenser, a collector, means arranged beneath the condenser for forcing the water of condensation to the collector, means for distributing the water of condensation over the condenser, a ventilator for creating a draft through the locomotive stack, and means for selectively causing the flow of the exhaust steam through the stack or to the condenser.

3. An economizer system for locomotives, comprising a condenser, a collector, means for forcing the water of condensation to the collector, means arranged beneath the condenser for distributing the water of condensation over the condenser, a ventilator for creating a draft through the locomotive stack, and means for selectively causing the flow of the exhaust steam through the stack or to the condenser.

4. An economizer system for locomotives, a condenser, a collector, means for forcing the water of condensation to the col-

lector, means for distributing the water of condensation over the condenser, a ventilator for creating a draft through the locomotive stack, and a valve for selectively causing 5 the flow of the exhaust steam through the stack or to the condenser.

In testimony whereof I affix my signature, in presence of two witnesses.

RODOLPHE RAU.
